T. LUND

FINISHING MACHINE

Filed Sept. 14, 1925

INVENTOR

Thomas Lund
By his Attorney,
Robert M. Howard.

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed September 14, 1925 Serial No. 56,266.

This invention relates to finishing machines for boots and shoes and is illustrated as embodied in a machine for burnishing the peripheries of the soles and heels of boots and 5 shoes.

For performing edge-setting operations on the soles of shoes of the better grades, it is the general practice to use edge-setting machines of the type employing vibratory edge-setting tools because of the high quality of work which such machines are capable of performing in the hands of skillful workmen. On the other hand, for a good deal of the less expensive work, edge-setting machines employing 10 rotary edge-setting tools are used, because such machines are less expensive, and their operation requires less skill on the part of the operators. Rotary edge-setting machines, however, are subject to the limitation that 15 rotary edge-setting tools are not well adapted for treating the portions of a sole edge closely adjacent to the breast of the heel because of the liability of scarring the heel if a rotary tool is operated too close to the heel 20 breast.

In view of the foregoing, it is an object of this invention to provide an improved burnishing machine having the characteristic advantages of burnishing machines employing 25 rotary burnishing tools, and which at the same time will overcome the difficulty above referred to. This object is attained in the illustrated construction by the provision of a novel edge-setting machine of the type employing both a vibratory burnishing tool 30 and a rotary burnishing tool, these tools, as herein illustrated, being positioned closely adjacent to one another to facilitate transferring work from one to the other and being 35 actuated from a common shaft, thus providing a simple, compact and efficient machine organization.

In many shoes the edge of the sole at the shank adjacent to the breast of the heel is 40 "square", that is, approximately at right angles to the tread surface at the outer side of the shoe shank and curved or oblique to the tread surface at the inner side of said shoe shank. Accordingly, another object of the 45 invention is to devise an improved burnishing tool of the vibratory type, which is constructed and arranged for use either upon square edge shanks or curved edge shanks, said tool, as illustrated, being provided with suitable

rand crease guiding projections adjacent to 55 the respective burnishing surfaces.

These and other features of the invention are described in the following specification taken in connection with the accompanying drawings, in which:

Fig. 1 is a perspective view of a finishing machine constructed in accordance with my invention;

Fig. 2 is a section through the tool-carrying shaft adjacent to the carrier for a vibratory tool;

Fig. 3 is a fragmentary view of a portion of the tool-carrying shaft showing an eccentrically formed portion thereof, much exaggerated; and

Figs. 4 and 5 are detailed views illustrating the application of my novel tool to the curved and square edges of a sole, respectively.

The illustrated burnishing machine, as 75 shown in Fig. 1, may be mounted either upon a pedestal 10 or upon a bench (not shown) and comprises a frame 12 in which there is supported a main shaft 14 directly connected to the shaft of a driving motor 16. A tool-carrying shaft 18 is also supported in bearings in the frame and suitably driven as by means of a chain (not shown), within a casting 19, from the main shaft 14. This shaft 18 projects at the left-hand side of the frame 12 80 and is provided with a rotary forepart burnishing tool 20 and a rotary shank burnishing tool 22. Thus these tools are adapted for treating shoes which, for example, have square sole edges on the outer sides of their shanks and curved edges on the inner sides of their shanks.

It will be understood that the surfaces of the forepart tool 20 are arranged for burnishing a so-called square sole edge which, as 95 above explained, extends approximately at right angles to the tread surface of the sole and may, accordingly, be used for burnishing a square edge of the shank of a sole up to a position slightly separated from the breast 100 of the heel. On the other hand, the shank burnishing tool 22 is adapted for treating a curved sole edge surface and is therefore suitable for treating a curved shank edge 105 from its junction with the forepart of the sole at the ball line, to a position slightly spaced from the breast of the heel upon the inside of the shoe.

Any suitable arrangement may be provided for heating these tools. In the illustrated construction the tool carrying shaft 18 is made hollow, and an electric heating unit 24 (Fig. 3) is inserted within the hollow shaft. Current may be supplied to such a unit in a well known manner by means of collector rings (not shown) which, in the illustrated machine, are mounted on the shaft 18 within a casing 26 formed integrally with the frame 12 of the machine.

The portion of the tool-carrying shaft 18 which lies between the rotary forepart tool 20 and a bearing 28 formed integrally with the frame 12 is made slightly eccentric. Such eccentricity, greatly exaggerated, is illustrated at 30 in Fig. 3. A bracket arm 32 formed upon the bearing 28 supports a pin 34 acting as a pivot for a tool-carrying arm 36 which is provided at its outer end with a stud 38 and a retaining spring 40, both of usual construction, by means of which a vibratory burnishing tool 42 is held upon the arm. The tool-carrying arm 36 is slotted at 44 and within this slotted portion rides a suitably formed block 46 provided with a bearing 48 surrounding and closely engaging the eccentric portion 30 of the tool-carrying shaft 18 which transforms the rotary movement of said shaft to a vibratory movement of the tool carrying arm 36 and the tool 42. As the arm 36 is moved the tool is given a vibratory movement up and down in a plane generally vertical but sloping inwardly away from an operator standing in front of the machine. It will be noted from an inspection of Fig. 1 that the outer left-hand edges of the tool-carrying arm 36 are chamfered to prevent possible interference between work being applied to the rotary forepart tool 20 and said arm. In order to facilitate treating both curved and square shank edges closely adjacent to the heel breast, the vibratory burnishing tool 42 is given a novel construction, as best shown in Figs. 4 and 5, from which it will be seen that it comprises a shank portion 50 recessed at 52 for the reception of the stud 38 of the tool-carrying arm 36 and notched at 54 for the reception of the end of the retaining spring 40. At the end of this shank portion 50 is mounted a burnishing head 56 which is provided with a so-called flat burnishing surface 58 and a curved burnishing surface 60 disposed side by side and separated by a rand crease guiding projection or lip 62, one side of which forms a continuation of the curved surface 60. This lip 62 lies alongside the flat burnishing surface 58 and is used by the operator to assist in guiding the work when a square-edged shank 64 is to be treated close to the heel breast. It will be understood that the so-called flat surface 58 is in reality slightly curved about an axis adjacent to the pin 34 (see Fig. 2) in a manner well understood in the construction of vibrating burnishing

tools. It will also be understood that the curved burnishing surface 60 is also slightly rounded about the same axis. Another lip 66, serving as a rand crease guiding projection, is also formed upon the tool adjacent to the other side of the curved burnishing surface 60 and this lip 66 is used by the operator when working upon curved shank surfaces 68 (Fig. 4) adjacent to the heel breast.

Preferably, and in order that the machine may be used for burnishing the peripheral surfaces of heels as well as the edges of soles, another tool-carrying shaft 70 is mounted in suitable bearings in the machine and driven in any desired manner from the main shaft 14 by means of driving connections contained within a protective casing 72. A heel-burnishing tool or pad 74 is mounted upon this shaft while upon the outer end of the shaft there is provided a beading tool 76 heated frictionally by means of a rubbing clamp 78 in a manner well understood in the art. If desired, a finishing brush 80 may be mounted upon the outer end of the shaft 14 in a position where it does not interfere with the application of work to either the tools upon the tool-carrying shaft 18 or those upon the other tool-carrying shaft 70. A receptacle 82 mounted upon the frame of the machine at the rear is utilized for holding cleaning and repairing materials or waxes.

In the presentation of work to the machine the operator will always hold a shoe with the tread face of the sole to the right (as viewed in Figs. 1, 4 and 5) and will present the edge of the sole on one side closely adjacent to the heel breast to the appropriate portion of the vibratory burnishing tool 42, then to the rotary burnishing tools 20 and 22 successively so that, with a substantially continuous movement of the shoe about an imaginary axis, the edge of the sole will be finished from the heel breast upon one side of the shoe up to a position closely adjacent to the heel breast on the other side. The work will then be carried back to the nearby vibratory tool 42 and the remaining portion of the sole will be treated by means of the proper surface on this tool, guiding the work by means of the corresponding rand crease guiding projection or lip 62 or 66 as the case may be. Thus when a shoe for a left foot is being treated, assuming that the shoe is of the type referred to and has a square shank sole edge on its outer side and a curved edge on its inner side, the operator may start holding the shoe with the toe pointing upward and apply the outer shank of the shoe to the burnishing surface 58 to finish the square edge of the shank closely adjacent to the heel breast. He then will transfer the shoe to the rotary burnishing tool 20 and with a single sweeping motion complete the burnishing of the forepart or square-edged portion of the sole of the shoe so that

the toe is then projecting downwardly. He then will transfer the shoe to the shank-burnishing tool 22 to finish the curved inner shank from the point of intersection of the 5 squared and curved edges of the sole up to a position slightly spaced from the heel breast at the inner side of the shank. The work will then be carried back to the vibratory tool 42, and guiding the work by means of the lip 10 66, the remainder of the curved edge of the shank will be treated upon the curved burnishing surface 60 close up to the breast of the heel. If it is desired to burnish the periphery of the heel, the shoe will also be applied to the 15 tools 74 and 76, respectively, and, if desired, the brush 80 may be used to give a final polish to all parts of the periphery of the bottom of the shoe.

A like sequence of operations will be carried out if a shoe for the right foot is being presented, except that the various surfaces will be treated in a reverse order, it being remembered that the shoe is always held with the tread face of the sole toward the right and will usually be presented in inverted position 20 from that in which the shoe for the other foot was presented, according to the wishes and habits of the operator.

Thus it will be seen that there is provided a 30 compact and an efficient machine of simple and rugged construction by means of which all of the periphery of the sole and heel of a shoe may be treated in successive operations upon tools positioned closely adjacent to one 35 another, which, in the case of the edge-setting tools, are actuated from a single shaft. The relative position of the various tools is of great consequence in facilitating the rapid manipulation of work and the presentation 40 thereof to the machine, because it enables an operative, with a minimum of movement and without changing his stance, to present all of the periphery of the sole from the heel breast line upon one side to the heel breast 45 line upon the other side in a series of operations which are substantially continuous with one another.

Having described the invention, what I claim as new and desire to secure by Letters 50 Patent of the United States is:

1. In a burnishing machine, a rotary shaft, a circular tool mounted on said shaft and provided with a burnishing surface on its periphery, said shaft being formed with an eccentric portion, a pivoted arm upon said machine having a slotted portion co-operating with the eccentric on said shaft to vibrate the arm, and a burnishing tool secured to the outer end of said arm for vibration therewith, 55 whereby the greater portion of the edge of the sole of a shoe may be burnished by means of the rotary tool and the portion adjacent to the heel-breast may be finished by means of the vibratory tool.

60 2. In a burnishing machine, a rotary shaft,

a rotary forepart burnishing tool secured to said shaft, a rotary shank burnishing tool secured to said shaft adjacent to said first tool, said shaft being provided with an eccentric portion adjacent to one of said tools, a tool-carrying arm associated with said eccentric portion and arranged to be vibrated thereby, and a burnishing tool secured to said arm for vibration therewith, whereby the greater portion of the edge of the sole of a shoe may 70 be burnished by means of the rotary tools and the portion adjacent to the heel-breast may be finished by means of the vibratory tool.

75 3. A burnishing machine comprising a rotary shaft, a forepart edge setting tool mounted for rotation with said shaft, a shank edge setting tool mounted for rotation with said shaft and adjacent to said first tool, said shaft having an eccentric portion adjacent to one of the tools, a tool carrying arm arranged to be vibrated by said eccentric portion of the shaft, and an edge setting tool secured to said arm for vibration therewith.

80 4. A burnishing machine comprising a rotary shaft, a rotary forepart edge setting tool secured to said shaft, a rotary shank edge setting tool secured to said shaft adjacent to the first tool, a tool carrying arm, an edge setting tool secured to said arm, and means connecting said arm with said shaft constructed and arranged to vibrate said arm and the tool carried thereby upon rotation of the shaft.

85 5. In a burnishing machine, a rotary shaft, a rotary forepart burnishing tool secured to said shaft, a rotary shank burnishing tool secured to said shaft adjacent to said first tool, said shaft being provided with an eccentric portion adjacent to one of said tools, a tool-carrying arm associated with said eccentric portion and arranged to be vibrated thereby, 90 and a burnishing tool secured to said arm for vibration therewith, said vibratory tool being provided with adjacent surfaces adapted to treat a curved shank edge and a square shank edge, respectively, whereby the greater portion of the edge of the sole of a shoe may be 95 burnished by means of the rotary tools and the portions adjacent to the heel-breast may be burnished by means of the vibratory tool.

100 6. In a machine for burnishing the edges of shoe soles, a vibratory tool having attaching means at one end and provided at the other end with adjacent edge burnishing surfaces, one of said surfaces being substantially flat so that it is adapted to treat a square edge portion of the sole, said adjacent edge burnishing surface having a curved contour receding toward the attaching means so that it is adapted to treat a rounded edge portion of the sole, and a rand crease guiding lip on 105 said tool between said surfaces projecting beyond both burnishing surfaces and so related to the flat surface that it will enter the rand crease to serve as a guide for the tool when the flat burnishing surface is applied to the 110 square portion of the edge of the sole, said 115 tool being vibrated.

120 7. In a machine for burnishing the edges of shoe soles, a vibratory tool having attaching means at one end and provided at the other end with adjacent edge burnishing surfaces, one of said surfaces being substantially flat so that it is adapted to treat a square edge portion of the sole, said adjacent edge burnishing surface having a curved contour receding toward the attaching means so that it is adapted to treat a rounded edge portion of the sole, and a rand crease guiding lip on 125 said tool between said surfaces projecting beyond both burnishing surfaces and so related to the flat surface that it will enter the rand crease to serve as a guide for the tool when the flat burnishing surface is applied to the 130 square portion of the edge of the sole, said 135 tool being vibrated.

receding burnishing surface being then adapted to overlie the shoe upper out of contact therewith.

7. In a burnishing machine, a vibratory tool provided with a substantially flat edge-burnishing surface adapted to treat a square sole edge and with an adjacent edge-burnishing surface having a curved contour adapted to treat a rounded sole edge, and a rand crease 10 guiding lip projecting from said tool between said surfaces arranged to enter the rand crease to guide the work with respect to the flat burnishing surface, one face of said lip forming a continuation of the curved burnishing surface.
8. In a burnishing machine, a vibratory tool provided with a shank and with a head having a burnishing surface disposed substantially at right angles to the shank of the 20 tool and with a curved burnishing surface angularly related to said shank, and guiding

lips projecting from said tool upon either side of the curved surface so that one of said lips is between the two surfaces and serves as a guide for work presented to the first named 25 surface and the other lip serves as a guide for work presented to the curved surface.

9. In a burnishing machine, a vibratory tool provided with a shank, a head having a burnishing surface disposed substantially at 30 right angles to the axis of the shank of the tool and with a curved burnishing surface angularly related to said axis, and guiding lips projecting from said tool on either side of one of said surfaces so that one of said 35 lips is between the two surfaces and serves as a guide for work presented to one surface and so that the other lip serves as a guide for work presented to the other surface.

In testimony whereof I have signed my 40 name to this specification.

THOMAS LUND.
